ADJUSTABLE WINDOW SHUTTER

Leon M. Kendall, Manchester, Maine, assignor
to Kenlane Manufacturing Company Inc., a
corporation of Maine

Application February 26, 1947, Serial No. 730,911

7 Claims. (Cl. 189—54)

1

This invention relates to adjustable window blinds which are to be secured permanently to the house at the sides of the windows.

The new adjustable blinds are made of two similarly shaped sections of thin sheet metal which can be overlapped to a greater or less extent, and which are especially shaped to give longitudinal stiffness and appearance similar to that of a wooden blind when secured to the house; and transverse reinforcing members are provided, of wood or metal, at the top and bottom of the blind and at the intermediate overlapping portion for securing the blinds to the house and providing transverse stiffness to the blind.

The new adjustable blinds are of simple and inexpensive construction and can be simply and readily applied to the house; and the adjustable nature of the blinds permits them to be used for windows of different heights.

The new blinds can be painted or enameled in different colors and in contrasting colors to match different standard colors of paint used in painting the houses or to give a contrasting and pleasing effect.

The blinds are made of two thin sheet metal sections, each with a wide central panel and with narrow side panels united together through short sections at right angles thereto and with in-turned edges at right angles to the edge sections, so that the two sections have longitudinal stiffness and when applied to the house will have much the appearance of a wooden blind or shutter with a wide central panel and narrow edge panels. The two sections are of generally the same shape except that the upper section is of a size such that it will overlap the lower section to a greater or less extent.

The transverse reinforcing members, which may be of wood or metal, are shaped to conform with the cross-section of the sheet metal sections. They can be separately provided and applied at the time the blinds are applied to the house or advantageously secured permanently to the sheet metal sections at the time they are made. Three transverse reinforcing elements are provided and are located at the top, bottom and overlapping portions of the blind. When separately applied, these are inserted when the blinds are applied to the house, as by nails or screws passing through the thin sheet metal and the reinforcing elements for securing the blinds to the house.

The reinforcing elements are advantageously applied to the sheet metal sections when they are

2

manufactured. In this case two of the transverse reinforcing elements are applied at the ends of the lower section and one at the top of the upper section, leaving the lower end of the upper section unobstructed so that it can slide over and overlap the lower section to the desired extent to give a blind of the proper height for the window.

When the transverse reinforcing elements are made of wood they are cut and shaped to conform to the cross-section of the sheet metal and with the sheet metal secured thereto by nails or screws, advantageously applied at the edges and at the narrow sections between the central and side panels. When the reinforcing elements are made of metal, such as sheet metal, they are similarly shaped to conform to the cross-section of the thin sheet metal sections and may be secured thereto by welding, riveting, etc.

20 For decorative purposes the adjustable blinds may also be provided with an outer removable panel or plate of sheet metal extending across the width of the central panel and having means for securing it in place so that different plates with different decorative designs thereon can be used and replaced as desired.

The adjustable sheet metal blinds of the present invention are so constructed that the two sections are nested together for shipping with one section overlapping the other for the greater part 30 of the length. When the transverse reinforcing members are applied when the blinds are made, the sections can be nested or overlapped for practically the entire length except for the transverse reinforced portion at the end.

35 When the adjustable blinds are to be secured to the house at the sides of the windows the lower section will be first applied and secured to the house and the upper section will then be overlapped to an extent which gives the proper 40 height of the blind and it will then be secured to the house, the lower part of the upper and outer section being secured at the same place at which the upper end of the lower section is secured. The result is to give a sheet metal blind 45 having much the appearance of a wooden blind with a central raised panel section of greater thickness than the side panels and with the in-turned edges of the sheet metal sections forming the sides of the blinds.

50 The invention will be further described in connection with the accompanying drawings illustrating certain embodiments thereof, but it is intended and will be understood that the invention is illustrated thereby but is not limited thereto.

In the accompanying drawings:

Fig. 1 shows a section of a house with two of the new adjustable blinds secured thereto at the sides of a window;

Fig. 2 is a front view of one of the blinds;

Fig. 3 is a top view of the blind of Fig. 2;

Fig. 4 is a transverse section taken on the line 4—4 of Fig. 2;

Fig. 5 is a longitudinal section taken on the line 5—5 of Fig. 2;

Fig. 6 is a view of the back of the blind and illustrating the adjustment of the sections, one position of the upper section being shown in continuous lines and another location in broken lines;

Fig. 7 shows a sheet metal plate which after bending will form a cap or cover for the top of the upper section, or a reinforcing element for the end of the section;

Fig. 8 shows the cap or cover formed by bending the sheet of Fig. 7;

Fig. 9 shows an alternative form of reinforcing member for the ends of the sections, this being made of a sheet of metal such as shown in Fig. 7;

Fig. 10 is a section taken on the line 10—10 of Fig. 2 showing the added decorative element and one means of securing it in place; and

Fig. 11 shows in four transverse end views, A, B, C and D, different steps in bending a sheet of thin sheet metal to form the sections of the blinds therefrom.

In the structures shown in the drawings, the adjustable blinds are made up of two sections, the upper section 1 overlapping the lower section 2 to a greater or lesser extent, the overlapping portion being indicated at 3. Each section is made up of a wide central panel 4 and side panels 5 joined together through sections 6 at right angles thereto and with inturned edges 7 forming the sides of the blinds.

The formation of these thin sheet metal sections is illustrated conventionally in Fig. 11 where A shows one end of a piece of sheet metal before bending, B shows the edges turned in to give the reinforced and strengthened edges, C shows these edges turned down to form the sides of the blind, and D shows the thin sheet metal when bent to final shape to form the wide central panel 4 and the side panels 5 united together through the short sections 6 at right angles thereto. The sheets of thin metal can thus be readily bent to form the reinforced edges, and shaped into the form of the finished blind sections, by ordinary metal working machinery used for bending and shaping the thin sheet metal. It will be seen that the reinforced edges 7 and the intermediate portions 6, between the central panel 4 and the side panels 5, are at right angles to the panels and give longitudinal stiffness to the panels even though made of thin flexible sheet metal. The inturned edges 7, being of double thickness, give a finished appearance to the back edges of the blinds and give increased lengthwise stiffness to the sections.

At the top of the upper panel, and at both ends of the lower panel, are transverse reinforcing elements 9 of a shape conforming to the cross-section of the bent sheet metal. As shown in Figs. 1 to 6, these sections 9 are of wood, cut or formed to the shape shown and with the sheet metal secured thereto by nails or screws 10 as illustrated in Figs. 3 and 4. The back edges of these reinforcing elements are even with the back edges of the sheet metal. The front portions of these elements are advantageously

curved somewhat, as indicated at 8 in Figs. 3 and 4, so that when the elements are applied to the sheet metal and secured thereto the central panel 4 will be similarly curved and held in close contact with the curved portion of the reinforcing member.

The two sections thus made can be painted or enameled and are then ready for shipment. The top section can overlap the lower section its entire length except for the reinforced portion at its end. And a number of blinds so constructed and nested together can be readily packaged and shipped.

When the blinds are to be applied, for example, as illustrated in Fig. 1, to a house 11 alongside a window 12 the lower section 2 is applied and secured to the house, as by nails or screws 13 passing through the thin sheet metal and through the lower reinforcing member. The upper section can then be applied with a sufficient overlap to give a blind of the required height of the window and similarly secured in place through nails or screws 13 applied through the thin sheet metal and the upper reinforcing element. Both sections are then secured to the building at an intermediate point by nails or screws passed through the overlapping sections and through the reinforcing element at the top of the lower section.

For decorative purposes the blinds are advantageously provided with removable sections 14, as shown in Figs. 1, 2 and 10, formed of thin sheet metal having various decorative patterns thereon, one of which is illustrated in Fig. 1, and which may be painted the same color as the central panel of the blinds or in contrasting colors. These removable sections have a length somewhat greater than the width of the middle panel of the blind and have provision at their ends for securing these sections in place, as by openings 17 in the intermediate sections 6 or bolts or other securing means. In the structure shown in Fig. 10 the thin sheet metal section 14 has end sections 15 and inturned projections 16 extending into openings 17 in section 6. Such removable sections can be readily inserted and removed and a series of sections can be provided with different decorative designs thereon to permit selection of the desired design for use in any particular case.

When the transverse reinforcing elements are made of wood they may be provided with an outer protective cap 18 of sheet metal, one such cap being shown in Fig. 8 as applied to the top of the upper section of the blind to protect the wood from exposure to the elements. A similar cap or cover can be applied at the bottom of the lower section of the blind.

A cap or cover 18 at the ends of the blinds, such as shown in Fig. 8, can be made from a single sheet of metal 19 cut and pressed as shown in Fig. 7 and bent along the broken lines shown in Fig. 7 to form the cap or cover shown in Fig. 8. Thus the intermediate section 20 of the sheet metal plate of Fig. 7 will form the top 20 of the cap or cover of Fig. 8, the end projections 21 of Fig. 7 will form the end portions 21 of Fig. 8, the back portion 22 of Fig. 7 will form the back of the cap or closure, the front portion 23 of Fig. 7 will form the central front portion of the cap overlapping the top of the middle panel 4 and the end sections 24 of Fig. 7 will form the sections 24 of Fig. 8 overlapping the side panels. The intermediate portions 6, in this construction, do not have any portion of the cap extend-

ing down over them. Openings 26 may be made in the removable caps to facilitate securing them in place by bolts or screws passing through the reinforced end portions of the blinds.

Instead of making the transverse reinforcing elements of wood, they may be made of metal. Fig. 9 shows such a reinforcing member 18 made from a single sheet of metal such as shown in Fig. 7 and formed into a reinforcing element similar to that of Fig. 8, but intended in this case to be located on the back of the thin sheet metal sections and secured thereto by welding or otherwise. Openings 27 may be provided in the reinforced ends of the blinds, as shown in Fig. 9, to facilitate securing the sections to the house.

When the blinds are made by forming the bent sheet metal sections and after the transverse reinforcing elements are secured thereto the sections can be painted or coated with enamel of any desired color or of contrasting colors. For example, the middle panels 4 may be painted white, and the rest of the sections black; or both the middle panel and the other portions of the blind may be painted a single color such as green or brown, etc. or with different shades of the same color or with contrasting colors. The added decorative panels 14 may similarly be provided with a design in a color which will harmonize with or contrast with the paint on the blind itself.

The blinds can be provided in standard colors or in standard contrasting colors to harmonize with or to contrast with the usual paint colors used in painting houses, thus giving the customer a selection to meet his particular needs.

The new adjustable blinds have the same advantages as solid wooden blinds in that they can be readily applied to the house alongside the windows by the use of nails or screws. They have the advantage of wooden blinds in that they do not crack or become distorted in shape as is likely to occur with wooden blinds made of improperly seasoned wood. And they have the advantage of being adjustable to windows of different heights instead of requiring different blinds for windows of different heights.

It will be understood that the blinds may be made of varying widths and that the sections may be made of varying lengths.

It will also be understood that variations and modifications can be made in the specific form and shape of the sheet metal sections and of the transverse reinforcing elements; and that the specific structures above shown illustrate the invention, but that the invention is not limited thereto.

From the foregoing description it will be seen that the invention provides adjustable window blinds made of two overlapping sections which can be readily removed from and applied to each other and made to overlap to a greater or lesser extent for convenience of shipment and to permit the use of the blinds for windows of different heights. It will also be seen that the blinds, although made of thin flexible sheet metal, will be given longitudinal rigidity by the shape of the sheet metal and will be given transverse rigidity by the transverse reinforcing elements.

The panel structures disclosed herein are claimed generically in my application Serial No. 19,694, filed April 8, 1948 for "Panel and Panel Structures." The panel structures are also disclosed in my application Serial No. 19,693, filed April 8, 1948, now Patent 2,602,199, for "Assem-

bled Awning Structures," the claims of which are drawn to awnings.

I claim:

1. A decorative adjustable sheet metal blind 5 to be secured to a house alongside a window thereof, said blind comprising two sections of thin sheet metal adapted to overlap each other in the lengthwise direction to a greater or lesser extent so as to correspond to the height of a window of a house, each of said sections being made of a single sheet of metal bent to form a wide central longitudinal panel at the front of the section, separate side panels respectively on opposite sides of the central panels intermediate portions at 10 approximately right angles to said panels and extending respectively forward to the front central panel, and edge sections at right angles to the side panels and extending toward the back of the section, and transverse reinforcing members 15 each having a shape conforming to the cross-section of the sheet metal sections for securing the sheet metal sections at the ends and at overlapping portions of the adjustable sections to the house alongside a window thereof.
2. A decorative adjustable sheet metal blind 20 to be secured to a house alongside a window thereof, said blind comprising an upper and lower section of thin sheet metal of similar cross-section, the upper section being adapted to overlap the lower section to a greater or lesser extent so as to correspond to the height of a window of a house, each of said sections being made of a single sheet of metal bent to form longitudinal edge sections at right angles to the 25 main section and extending toward the back of the section, two transverse reinforcing members having a shape conforming to the cross-section of the lower sheet metal section and secured to the ends thereof, a similar transverse 30 reinforcing member having a shape conforming to the cross-section of the upper sheet metal section and secured to the upper end thereof, whereby the blind can be secured to a house alongside a window thereof in overlapping relationship by securing devices passing through the top of the upper section and the top reinforcing element, the bottom of the lower section and the lower reinforcing element and through the overlapping sections and the reinforcing element at 35 the top of the lower section.
3. A decorative adjustable sheet metal blind 40 to be secured to a house alongside a window thereof, said blind comprising two sections of thin sheet metal adapted to overlap each other in a lengthwise direction to a greater or lesser extent so as to correspond to the height of a window of a house, each of said sections being made of a single sheet of metal bent to form a wide central longitudinal front panel, separate 45 side panels respectively on opposite sides of the central panel, intermediate portions at approximately right angles to said panels and extending back from the central panel to the respective side panels, and longitudinal edge sections respectively at right angles to the side panels and extending back therefrom, transverse reinforcing members of wood having a shape conforming to the cross-section of the sheet metal sections and secured to the top and bottom of one section 50 and to one end of the overlapping section, whereby the two adjustable sections can be adjusted to different heights for different windows and secured to the house alongside a window thereof in overlapping relationship by fastening elements 55
4. A decorative adjustable sheet metal blind 60 to be secured to a house alongside a window thereof, said blind comprising two sections of thin sheet metal adapted to overlap each other in a lengthwise direction to a greater or lesser extent so as to correspond to the height of a window of a house, each of said sections being made of a single sheet of metal bent to form a wide central longitudinal front panel, separate side panels respectively on opposite sides of the central panel, intermediate portions at approximately right angles to said panels and extending back from the central panel to the respective side panels, and longitudinal edge sections respectively at right angles to the side panels and extending back therefrom, transverse reinforcing members of wood having a shape conforming to the cross-section of the sheet metal sections and secured to the top and bottom of one section and to one end of the overlapping section, whereby the two adjustable sections can be adjusted to different heights for different windows and secured to the house alongside a window thereof in overlapping relationship by fastening elements 65
5. A decorative adjustable sheet metal blind 70 to be secured to a house alongside a window thereof, said blind comprising two sections of thin sheet metal adapted to overlap each other in a lengthwise direction to a greater or lesser extent so as to correspond to the height of a window of a house, each of said sections being made of a single sheet of metal bent to form a wide central longitudinal front panel, separate side panels respectively on opposite sides of the central panel, intermediate portions at approximately right angles to said panels and extending back from the central panel to the respective side panels, and longitudinal edge sections respectively at right angles to the side panels and extending back therefrom, transverse reinforcing members of wood having a shape conforming to the cross-section of the sheet metal sections and secured to the top and bottom of one section and to one end of the overlapping section, whereby the two adjustable sections can be adjusted to different heights for different windows and secured to the house alongside a window thereof in overlapping relationship by fastening elements 75

passing through the sheet metal sections and the wooden transverse reinforcing elements.

4. A decorative adjustable sheet metal blind to be secured to a house alongside a window thereof, said blind comprising two sections of thin sheet metal adapted to overlap each other in the lengthwise direction to a greater or lesser extent so as to correspond to the height of a window of a house, each of said sections being made of a single sheet of metal bent to form a wide central longitudinal front panel, separate side panels respectively on opposite sides of the central panel, intermediate portions at approximately right angles to said panels and extending back from the central panel to the respective side panels, and longitudinal edge sections respectively at right angles to the side panels and extending back therefrom, transverse reinforcing members of sheet metal having a shape conforming to the cross-section of the sheet metal sections and secured to the top and bottom of one section and to one end of the overlapping section, whereby the two adjustable sections can be adjusted to different heights for different windows and secured to the house alongside a window thereof in overlapping relationship by fastening elements passing through the sheet metal sections and the sheet metal transverse reinforcing elements.

5. An adjustable blind such as defined in claim 1 having wooden transverse reinforcing elements and having a thin sheet metal cap of a shape conforming to the cross-section of the sheet metal sections for covering the top of the blind.

6. An adjustable sheet metal blind as defined in claim 1 characterized in that the central longitudinal front panel of each section is symmetrically curved outwardly between the intermediate portions of the section.

7. A decorative adjustable sheet metal blind to be secured to a house alongside a window thereof, said blind comprising upper and lower sections of similar cross-section with the upper section overlapping the lower section, each of said sections comprising a facing of thin sheet metal and being of similar contour so that the lower portion of the upper section overlaps the

10
15

20
25

upper portion of the lower section in a metal to metal contact, each of the facings of said sections being made of a single sheet of metal bent to form a wide central longitudinal front panel, separate side panels respectively on opposite sides of the central panel and offset rearwardly therefrom by intermediate portions at approximately right angles to said side panels and extending back from the central panel to the respective side panels, and longitudinal edge sections respectively at right angles to said side panels and extending back therefrom, two transverse reinforcing members having a shape conforming to the cross-section of the lower sheet metal section and secured respectively to the ends thereof, and a similar transverse reinforcing member having a shape conforming to the cross-section of the upper sheet metal section and secured to the upper end thereof, said transverse reinforcing members extending generally at right angles to the face of the sections and each having a straight back edge coincident with the respective back edges of the edge sections of the sheet metal sections to which the reinforcing members are secured, said sections being open at the back.
